UNITED STATES PATENT OFFICE.

SAMUEL SKLAR, OF BROOKLYN, NEW YORK.

SAFETY-STIRRUP.

1,276,819.

Specification of Letters Patent. Patented Aug. 27, 1918.

Application filed September 8, 1917. Serial No. 190,297.

To all whom it may concern:

Be it known that I, SAMUEL SKLAR, citizen of the United States, resident of Brooklyn, county of Kings, and State of New

5 York, have invented certain new and useful Improvements in Safety-Stirrups, of which the following is a specification.

This invention relates to improvements in stirrups, and particularly to types used in 10 connection with riding saddles in which the foot of the rider is inserted and supported.

The principal object of the invention is to provide a saddle-stirrup which may be safely used by a rider, the foot-rest of the stirrup 15 being automatically released by contact with the upper portion of the foot should the rider be thrown from the saddle so that the foot is released, but held against inadvertent displacement.

20 This and other like objects are attained by the novel construction and combination of parts hereafter described and shown in the accompanying drawings, forming a material part of this disclosure, and in which—

25 Figure 1 is a perspective view showing a saddle stirrup made in accordance with the invention.

Fig. 2 is a side elevational view of the same, looking from the opposite side and 30 showing the stirrup open.

Fig. 3 is an enlarged fragmental sectional view taken through its upper portion.

Fig. 4 is a sectional view taken on line 4—4 of Fig. 3.

35 Fig. 5 is a fragmental perspective view of the detaching plate, and

Fig. 6 is a fragmental front elevation of the same.

In the drawings, the numeral 10 designates a strap by which the stirrup is supported, the looped end 11, of the strap being held by the button 12, in such manner that it can be disengaged from the eye 14, affixed on the top 15, of the stirrup side 16, 40 engaged by the hinge joint bolt 17 with a similarly shaped side 18, the sides 16 and 18 forming together an arch in the usual manner.

The lower end of the element 16 is bifurcated, and has passing through the forked ends 19, a screw 20 or similar securing means upon which is pivoted a leaf 21, formed with the corrugated foot-rest 22, the opposite end having a raised stem 23, in 45 which is rotatably mounted a roller 24, the

stem carrying the roller being receivable in a slot 25, formed in the lower end 26 of the side 18 the roller being supported upon the solid material at the end of the slot.

A bent flat spring 28 is secured on the side 18, by the screw 29, and is engaged below the foot-rest 22, in such manner as to turn the same downwardly immediately upon the release of the stem 23.

An arcuately curved plate 30, having enlarged flat extensions 31, at its ends carrying rollers 32, adapted to engage with the sides 16 and 18, of the stirrup frame, and be guided by the same, is placed partially over and beyond the foot-rest 22, and has engaged with it an upright 33, having an open slot 34, slidably engaged with a sleeve 37 mounted on the bolt 17 and held operatively between the extending guides 35 and 36 by the nut 39.

55 Secured in the upright 33 is a pin 38, the same extending outward upon one side and making contact with a detent 40, pivoted on the pin 41, passing through a recess 42 formed in the side 16, and being pressed normally downward by the spring 44, secured by the screw 45 in the side 16.

The detent extends through a slot 46, formed in the side 18, through which passes a fixed pin 47, the same being engaged by 60 an acutely formed hook 48 on the lower side of the detent which is further formed with an operating hook extension 49 by means of which it may be manipulated, and which also acts as a limit or stop controlling the 65 opening between the sides 16 and 18 when the detent is raised, the sides separating under the pressure of the coiled spring 50 encircling the bolt 17 within recesses 52 and 54 formed respectively in the sides 16 and 18, the same being interlockingly engaged as shown in Figs. 3 and 4.

In operation, the parts being positioned as shown in Fig. 1, the foot is placed upon the foot-rest 22, and the stirrup used in the ordinary manner.

Should, however, the foot be raised by accident or otherwise so as to press the plate 32 upward, the pin 38 comes in contact with the detent, raising the hook from the fixed 105 pin 47 permitting the sides 16 and 18 to be forced apart by the spring in the recess surrounding the bolt 17, thereby withdrawing the stem 23 from the slot 25, this action being facilitated by the roller 24 and permit- 110

ting the spring 28 to pull the foot-rest downward, thereby freeing the foot from the stirrup in an obvious manner.

As the release plate 30 is guided on the front of the sides 16 and 18 it is protected against inadvertent displacement as by entanglement with brush, etc., and will not act unless considerable pressure is brought to bear upon it.

10 Having thus described my invention what I claim as new and desire to secure by Letters Patent, is,—

15 1. A saddle stirrup comprised of a pair of hingedly engaged, downwardly extending sides, means for holding said sides in operative position, a foot-rest hingedly engaged with one of said sides, a stem formed with said foot-rest enterable into an opening formed in the other of said sides, a sliding plate arranged over said foot-rest, and means combined therewith for releasing said foot-rest, when said plate is moved upward.

20 2. In a saddle stirrup comprising a pair of hingedly engaged sides, a foot-rest hingedly engaged with one of said sides, an extension formed with said foot-rest engageable with the other of said sides, means for normally holding said sides in operative position, means for releasing said sides, means for opening said sides outwardly whereby said foot-rest is disengaged and means for turning said foot-rest downward when released.

25 3. In a riding saddle stirrup, the combination with a pair of downwardly extending sides, a hinge by which said sides are joined together at their upper ends, a detent pivotally engaged with said sides hav-

ing a part enterable through the other of said sides by means of which it is held in operative position, a sliding plate having end projections; rollers carried in said projections contractible with said sides, an upright on said plate, means carried by said upright for disengaging said detent, a foot rest hingedly engaged with one of said sides, an extension formed therewith, a roller in said extension, said roller being adapted to engage with an opening formed in the other of said sides, and a spring adapted to press said sides apart thereby releasing said foot rest co-incidently with the disengagement of said detent.

4. In a riding saddle stirrup, the combination with a support strap, and an eye with which said strap is engaged, of a pair of separable curved side elements hingedly engaged at the upper end thereof, said eye being rigid with one of said side elements, a foot-rest hinged at the lower end of one of said side elements, a stem formed with said foot-rest adapted to enter a recess formed in the other of said side elements, a roller carried in said stem, a spring adapted to move said foot-rest downward when released, means for holding said side elements in operative position, an arcuate plate arranged partially over said foot-rest adapted to make contact with a foot, means for guiding said arcuate plate vertically, means formed with said arcuate plate adapted to release said holding means, and means for separating said side elements when released.

In testimony whereof I have affixed my signature.

SAMUEL SKLAR.
